(57) **CLAIM**

I Claim the ornamental design for a mountain vehicle bar with an ergonomic grip, as shown and described.

DESCRIPTION

FIG. 1 is a Front view of my new design;

FIG. 2 is a Back view thereof;

FIG. 3 is a Top view thereof;

FIG. 4 is a Bottom view thereof;

FIG. 5 is a Right side view thereof; and,

FIG. 6 is a Left side view thereof.

The novel features of my new design are its inverted "U" shape and ergonomic curves.
